UNITED STATES PATENT OFFICE.

HANS E. THEISEN, OF MUNICH, GERMANY.

APPARATUS FOR COOLING, WASHING, AND MIXING GASES.

1,131,966.

Specification of Letters Patent. Patented Mar. 16, 1915.

Application filed June 16, 1914. Serial No. 845,379.

To all whom it may concern:

Be it known that I, HANS EDUARD THEISEN, citizen of the United States of America, residing at Munich, Bavaria, Germany, have 5 invented certain new and useful Improvements in Apparatus for Cooling, Washing, and Mixing Gases; and I do hereby declare the following to be a full, clear, and exact description of the invention, such as will 10 enable others skilled in the art to which it appertains to make and use the same.

My invention relates to gas washing apparatus of the type wherein disintegrator members mounted for rotation on a horizontal shaft impel the gas through the apparatus in a direction counter to that of the washing fluid used for cleansing the gas. The gas admission opening is arranged at or near the base of the apparatus, while the 15 fluid supply means is near the top thereof. By this arrangement, the hot, dirty, raw gases which enter the apparatus come into intimate contact with a considerable body of fluid which is sprayed or projected toward 20 the gas admission passage, and in this manner the gas is subjected to a cooling and cleansing action prior to its reaching the disintegrator members.

Two embodiments of the invention are 25 shown in the accompanying drawing, in Figures 1 and 2 and Figs. 3 and 4 respectively, Fig. 1 being a side view, partly in section, Fig. 2 a vertical section perpendicular to the plane of Fig. 1, Fig. 3 a side view, partly broken away and in section, and Fig. 4 a view perpendicular to the plane of Fig. 3, partly in section.

Referring in the first instance to the construction shown in Figs. 1 and 2, the gas to 30 be treated is admitted at A to an annular chamber b surrounding a multiple ring of beaters B fixed to a disk g mounted upon a horizontal shaft, the admission of the gas being below the beaters, as indicated by the 35 arrows I. The stream of gas meets a stream of sprayed water issuing from between the beaters as indicated by the arrows II, and the gas passes from the chamber b through the ring of beaters in the opposite direction 40 to the water. The water which has passed through the beaters or disintegrator members, flows out of the casing through the discharge ducts 10. In order that the proportion of gas to water is approximately uniform 45 all around the ring of beaters, the

chamber b is enlarged toward the bottom, this being the part where the main body of gas enters, and where the spray is densest by reason of gravity.

From the ring of beaters B the gas flows 50 to a fan F, and in order that the flow of gas to the fan may be as regular as possible a plate d is placed between the beaters and the fan, with a suitably dimensioned central aperture therein.

With the construction shown in Figs. 1 and 2 a small part of the gas is liable to have access to the bearings and packing, and as the gas may be very hot and dirty this is not desirable. This disadvantage is 55 obviated in the construction shown in Figs. 3 and 4. In this construction the gas is admitted at g* on both sides of a revolving beater disk b*, the beaters of which revolve between fixed baffle members b* on the 60 walls of the chamber. These baffle members may be rods, perforated plates or rings, angle irons or the like. The water is admitted through siphon d*, annular conduit e and pipe f, so that it flows outward on both sides 65 of the beater disk and out of the casing through the discharge ducts 10*. The gas is admitted at the lower part of the chamber 70 around the beaters, this lower part being enlarged, as described with reference to Figs. 1 and 2. The gas is supplied under 75 pressure, or sucked through the apparatus, and flows to the beaters as indicated by the arrows 1 and 2, meeting the streams of water or spray indicated by the arrows 3. The 80 washed gas passes out on both sides at h, as indicated by the arrows 4. This construction 85 has the important advantage that the gas cannot come into contact with bearings and packing until it has been cooled and 90 washed. The apparatus is entirely symmetrical on both sides of the beater mechanism, so that the load on the shaft is evenly 95 distributed, and the drive is easy.

What I claim as my invention and desire to secure by Letters Patent of the United States is:—

In apparatus for the purpose set forth, the combination of a shaft, annular beaters carried thereby and adapted to project liquid centrifugally, a casing inclosing said beaters and forming a chamber about the same; the upper portion of said casing being concentric with said beaters and the lower portion of said casing having its op- 105

posite walls gradually divergent whereby the lower part of said chamber is of greater area than the upper part thereof, means for initially admitting gas to said apparatus through the lower enlarged part of said chamber, and means for supplying liquid to said beaters.

In testimony whereof I hereunto affix my signature in the presence of two witnesses.

H. E. THEISEN.
